UNITED STATES PATENT OFFICE.

GEORGE JOSEPH CAPEWELL, OF CHESHIRE, CONNECTICUT.

GUIDE FOR ROLLER-DIES.

SPECIFICATION forming part of Letters Patent No. 393,356, dated November 27, 1888.

Application filed March 20, 1888. Serial No. 267,809. (No model.)

To all whom it may concern:

Be it known that I, GEORGE JOSEPH CAPEWELL, of Cheshire, in the county of New Haven and State of Connecticut, have invented certain new and useful Improvements in Roller-Die Metal-Forming Machines, of which the following is a full, clear, and exact description, whereby any one skilled in the art can make and use the same.

10 My invention relates to the class of metal-forming machines in which a series of roller-dies are arranged in succession in pairs, and having between the said dies a passage or guideway that controls the direction of movement of the blank operated upon by the dies, and also determines its position for presentation to each succeeding pair of dies.

15 The object of my improvement is to provide a guideway having means for turning the blank upon its lengthwise axis while passing through the guideway, the said device being capable of directing imperfect as well as perfect blanks, and also of handling blanks of varying lengths.

20 My invention, as herein described and illustrated, is embodied in a machine for making horseshoe-nails, and in such machine a spiral guideway has been used that may be best described as a tube having a way or opening lengthwise through it, oblong in cross-section, 25 and having a lengthwise twist that forms a spiral passage that causes a blank to make a quarter-turn in passing through it. Such a guideway has the objection that a crooked blank will jam in it, and that one above a certain length cannot pass through it. It often 30 happens where a nail is formed by compression in successive steps upon opposite sides after making a quarter-turn that a slight fault—as a bend that stops the machine when using the old form of way—could be rolled out and a perfect nail produced if the blank could be passed to the next set of roller-dies, it being understood that the machine to which my invention refers is one in which the pairs of dies 35 are arranged with their axes parallel and with the forming parts of the dies in a vertical plane, the nail turning as it passes between successive pairs of rolls and being pressed first widthwise, then depthwise to elongate the 40 shank.

45 My improvement consists in a guideway

formed in a block, with one or more of the walls provided with an inwardly-projecting shelf or guide terminating short of the end of the way or channel in a rather abrupt slope or 55 turn, a peculiar feature of the guideway being that its bounding walls forming the opening or guideway are substantially parallel and have no spiral twist; and it further consists in a sectional guide-block partible lengthwise, 60 having a straight guideway with an inward projecting guide on one or more sides located within or terminating at one end short of the end of the channel.

65 It further consists in the details of the several parts making up this sectional block, whereby it may be separated if clogged by being pushed directly apart, or by rocking on either edge; and it further consists in the combination of the sectional block having its peculiar guideway, in combination with the roller-dies, and in the details of the several parts and their combination, as more particularly hereinafter described, and pointed out in the 70 claims.

75 Referring to the drawings, Figure 1 is a detail view, in elevation, of part of the front of a nail-making machine, illustrating the relative location of the roller-dies and the guideway between them, and also illustrating the 80 position of the nail-blank as it enters the upper pair of dies and as it leaves the lower pair. Fig. 2 is a detail front view of one-half of a guide-block of the prior art, having the spiral guideway. This view also shows three sections of the block taken on planes denoted by dotted lines opposite the sections. Figs. 3, 4, 5, 6, and 7 are plan views, each showing the guideway in one-half of the guide-block having modifications of the guide, each of these 85 views showing, also, sections of the guide-blocks on a plane denoted by the dotted line opposite the guide-block. Fig. 8 is a detail view in cross-section of part of the front of a nail-making machine, taken on a horizontal plane 90 passing through the guide-block, and also showing part of the trip mechanism for stopping the machine when the guideway becomes clogged. Fig. 9 is a cross-sectional view through the 95 guide-block. Fig. 10 is a cross-sectional view 100 of the guide-block shown as opened by rocking on one edge. Fig. 11 is a detail cross-sec-

tional view of the portable guide-block, showing stops along each edge against which the outer section pivots in turning.

In the accompanying drawings, the letter *a* 5 denotes the front of a nail-making machine containing the parts directly relating to my within-described invention.

The letter *b* denotes the upper pair of roller-dies, *c* the lower pair of roller-dies, and *d* 10 the guide-block located between the upper and lower pair of roller-dies. The nail-blank *e* enters the guideway from the pair of dies *b* after it has been operated upon edgewise by the dies, and in passing through the guideway it makes 15 a quarter-turn, so that the pair of roller dies *c* operate upon it flatwise, these two positions of the nail blank *e* being represented in Fig. 1 of the drawings.

In the guide-block *f* of the prior art there is 20 a spiral guideway, *f'*, formed when the two sections of the block are united, as by means of the dowels, each wall being continuous and unbroken and turning spirally, as is clearly shown by the several sections in Fig. 2 of the 25 drawings.

The turning of the blank in the old guideway is effected by the contact of the blank with opposite sides of the guideway. In my improved form of guideway the walls are 30 straight from end to end, as distinguished from twisted, and depend upon the guide that consists of a sloping projection located or originating about midway of the guide-block and forms the means of turning the blank. For 35 example, in Fig. 3, in the guide-block *g* the guideway *g'* slopes upward from a point just above the middle section, so that the blank *e*, when it reaches the end of this guide, has one corner—the left as the figure is looked at—40 lifted, so that it is turned from the position it occupied, as shown in dotted lines in the first section, to the position shown in the second section, and finally to that shown in the third section, in which latter position it is turned 45 one-quarter around, and is presented to the next pair of dies when it emerges to be operated upon flatwise of the nail when it enters the guideway, after having been operated upon edgewise of the nail.

50 The several modifications of guide-blocks shown at *h* and *h'* in Fig. 4, *i* and *i'* in Fig. 5, *j* and *j'* in Fig. 6, and *k* and *k'* in Fig. 7 are alternate forms of the same device, having in each the straight guideway with walls interrupted in their continuity on one or more of the opposite sides by the inwardly-projecting guides that are located within the length and substantially in the central portion of the guideway, existing as somewhat abrupt

breaks. It is essential to the perfect operation of a nail-making machine that the guide-blocks should be portable lengthwise, so that the line of passage of the blank from its entrance to its delivery from the machine may be accessible, and for the further purpose of 65 enabling the machine to be automatic in stopping any obstruction of the passage, causing the outer section, as *l*, (see Fig. 8,) to be forced out against the lever *m*, that operates upon the trip device *n* and connected mechanism that 70 stops the machine. This outer section, *l*, of a guide-block may be pushed directly outward; or it may be rocked upon one corner, as shown in Fig. 10, the tapered form of dowel *l'* 75 permitting the block to rock or turn on either edge. As a modification of the dowel, or in addition to it, I may make use of the stop *o*, that is a projecting flange along the edges of the inner guide-block that forms the fulcrum upon which the block may turn. 80

85 My invention is not limited to any specific form or special arrangement of the guide, nor to the number of faces of the guideway upon which it shall be arranged, as it is evident that this inwardly-projecting guide may be modified as to its form and location by the ordinary skill of one versed in the art without departing from the idea involved.

I claim as my invention—

1. In a nail-making or like machine of the 90 within-described class, a guide-block having a straight guideway, as distinguished from a spiral or twisted one, the said guideway continuous therethrough and with an inward projecting guide formed on one or more of the 95 walls, all substantially as described.

2. In combination with two sets of roller-dies, a sectional guideway located between the dies and having a passage through said guide-block located in the plane of the dies, the said 100 guideway having an inward projecting guide, whereby a blank of metal is caused to make a quarter-turn in passing through the guideway, all substantially as described.

3. In combination with a nail-making machine having two or more pairs of roller-dies, a sectional guide-block located between the pairs of dies, the lever of the stop-motion mechanism normally in contact with the outer guide-block section, and the tapered tenons, 105 whereby the two sections of the guide-block are held against sliding motion on each other, all substantially as described.

GEORGE JOSEPH CAPEWELL.
